UNITED STATES PATENT OFFICE.

WILLIAM MURPHY, OF BUFFALO, NEW YORK, ASSIGNOR, BY MESNE ASSIGNMENTS, TO THE NATIONAL CASH REGISTER COMPANY, OF DAYTON, OHIO, A CORPORATION OF OHIO, (INCORPORATED IN 1906.)

CASH-REGISTER.

No. 875,669.

Specification of Letters Patent.

Patented Dec. 31, 1907.

Application filed August 8, 1904. Serial No. 219,928.

To all whom it may concern:

Be it known that I, WILLIAM MURPHY, a citizen of the United States, residing at Buffalo, in the county of Erie and State of New York, have invented certain new and useful Improvements in Cash-Registers, of which I declare the following to be a full, clear, and exact description.

This invention relates to printing attachments for cash registers and has for its object to provide an improved device for locking the paper feeding mechanism during certain stages of the operation of the machine.

This particular device is shown as applied to the style of machine set forth in Patent No. 580,378 to Joseph P. Cleal and Frank A. Reinhard, dated April 13, 1897, although from a consideration of the nature of these improvements it will be obvious to those skilled in the art that these devices may be applied to various other types of machines.

With these and incidental objects in view, the invention consists in certain novel features of construction and combinations of parts, the essential elements of which are set forth in appended claims and a preferred form of embodiment of which is hereinafter specifically described with reference to the drawings which accompany and form part of this specification.

Of said drawings: Figure 1 represents an end elevation of the machine to which these improvements have been applied. Fig. 2 represents an enlarged detail view of the feeding mechanism for the detail strip, showing the printing carriage in raised position.

In the general operation of this character of machine which is at present well known in the art, the keys 10 are depressed to represent the amount of the purchase and upon the operation of a crank handle (not shown herein but shown in the aforesaid patent), certain operating elements are set to differential positions as determined by the keys, the counter is operated, and the printing of the amount corresponding to the keys depressed is also effected. This printing of the amounts is secured from type carriers or segments 11 which are suitably connected to the aforesaid differentially movable operating elements as described in said patent so that they assume positions corresponding to the values of the keys depressed. The revolution of the main operating handle of the machine imparts at each operation of

the machine a complete revolution to the operating shaft 12 to which shaft is made fast a disk 13 in which disk is formed a cam groove 14 as shown in dotted lines in Fig. 1 into which groove projects a pin 15 fast upon the upper end of a paper carriage 16. It will be noted that the shape of the cam groove 14 is such that the carriage 16 which slides between suitable guide pieces 17, will be reciprocated twice at each revolution of the disk 13 and thereby at each operation of the machine, the first reciprocation being utilized for the printing of a check and the second for printing on the detail strip. The check paper is fed from a storage roll 18, through a chute 19 and thence between certain feed rollers which are operated by the main operating shaft of the machine to feed the paper over a platen roller 20 which is mounted upon the paper carriage 16, this roller being mounted in juxtaposition to the printing line of the type carriers 11. A suitable knife carried upon the carriage 16 serves to sever the check to permit the same to be ejected from the machine by means of an ejector 21 which is suitably operated from the shaft 12 at each operation of the machine.

On the lower portion of the carriage 16 is mounted a detail strip supply roller 22 from which the detail strip 22a is unwound and is then fed over the platen roller 20 and back to the winding roller 23. The supply roller 22 is provided with a ratchet wheel 24 and the winding roller 23 is supplied with a similar ratchet wheel 25, the latter wheel being engaged by a spring-pressed retaining pawl 26.

For the purpose of feeding the detail strip at each operation of the machine an arm 27 is provided which is pivoted upon the same shaft 28 with the winding roller 23 (see Fig. 2), and this arm 27 carries a feed pawl 29 which engages the ratchet wheel 25. Pivoted to the main frame of the machine at 30 is a link 31 which at its lower end is formed with a slot 32 in which plays a pin 33 carried upon the middle portion of the arm 27. It will thus be apparent that when the carriage 16 is carried upward for printing in the manner previously described the shaft 28 carrying the arm 27 is of course carried upward but the outer end of the arm 27 cannot be carried upward because of the connection with the stationary link 31 and therefore the

feed pawl 29 slips idly over the ratchet wheel 25, until the carriage 16 returns downward to its normal position during which time the pawl 29 engages the ratchet 25 and feeds the detail strip during this return movement of the carriage. As stated above the carriage is given a double reciprocation, but the intermediate reciprocation is a slight one being merely for the purpose of withdrawing the carriage from the type to permit the check to be ejected and then again forcing the hammer against the type to print upon the detail strip. This intermediate downward and upward movement of the carriage need of course be very slight and during such movement there is no feed of the detail strip due to the fact that the length of the slot 32 in the link 31 is such that the arm 27 will not begin to be operated by the link 31 during this short extent of the intermediate reciprocation of the carriage. This provision for the discontinuance of the feed during this reciprocation is an adjunct of the locking feature to be presently described. The general construction however of the parts heretofore set forth is substantially the same as that described in the aforesaid patent and contained in machines now extensively marketed.

The particular feature of the present improvement will now be described. Machines of this particular character are usually provided with a device for preventing the issuance of a check, this device in the present instance being regulated by a so-called "On" and "Off" knob 40 which when turned by the operator effects the discontinuance of the feed of the check paper so that no check is issued upon that operation of the machine; and as the construction of this "On" and "Off" knob and its attendant parts is well known no further description of the same will be given. When the check feed is discontinued in such manner, the carriage 16 is nevertheless reciprocated twice at each operation of the machine and under ordinary circumstances of course simply causes both impressions to be taken upon the detail strip but since there is no feed of the detail strip during this time, the impressions would be taken one on top of the other since no check strip intervenes between the type and the detail strip. This has laid the machine open to manipulation by permitting the operator, when the check feed is thus discontinued, to advance the detail strip between the successive impressions and thereby print upon the detail strip a double record for a single transaction, thus of course producing a false entry in the machine. To prevent such manipulation means have been provided for preventing such advancement of the strip while the platen is within the range of its operative effectiveness, the particular means in the present case constituting duplex pawls 50 and 51, which are pivoted at 52 to the lower

portion of the carriage 16 between the two ratchet wheels 24 and 25. The upper ends of these pawls are normally forced toward each other by means of a spring 53 compressed between the lower ends, and each pawl has upon its outer side a single tooth 54 arranged to engage their respective ratchet wheels.

Pivoted to the main frame at 55 is a link 56 the upper end of which carries a pin 57 which projects laterally through a slot formed in the carriage 16 and between the two pawls 50 and 51. The inner sides of these two pawls are so shaped that the pin 57 can normally rest between them in the normal position of the carriage so that the spring 53 can force the upper ends of the pawls together far enough to withdraw the teeth 54 from their respective ratchet wheels; however as soon as the carriage 16 has been moved upward to printing position, the pawls are both forced into engagement with their respective ratchet wheels because of the lessening of the distance between the two pawls near their pivotal points so that the pin in going down between the pawls forces them apart in the manner described. This condition obtains while the platen roller 20 is within its range of effectiveness, that is while it is still in position again to be reciprocated to cause the second impression to be taken, so that the locking of the ratchet wheels 24 and 25 by the pawls 50 and 51 absolutely prevents any feeding of the paper at this point. As soon however as the carriage has completed its printing movement and has disengaged sufficiently to cause the arm 27 to begin the normal feed of the strip in the manner previously described, the spreading pin 57 is at this time in the widened portion between the two pawls 50 and 51 so that the pawls may spring back to normal position and release the ratchet wheels 24 and 25 to permit the normal feed of the strip.

Of course it might be sufficient in some cases to lock merely one of the detail strip rollers but it would seem preferable to lock both of them in order to prevent manipulation of any slack paper, and of course various modifications of the above devices might well be used not only in this type of machine but in others.

While the form of mechanism here shown and described is admirably adapted to fulfil the objects primarily stated, it is to be understood that it is not desired to confine the invention to the one form of embodiment here disclosed, for it is susceptible of embodiment in various forms all coming within the scope of the claims which follow.

Having thus described my invention, what I claim as new and desire to secure by Letters Patent is:

1. In a printing attachment, the combination with type carriers, a paper support, a

platens, and means for bringing the platen and type together to produce an impression upon the paper; of means for absolutely preventing the advancement of said paper while the platen is within the entire range of printing effectiveness.

2. In a printing attachment, the combination with type carriers, a paper support, a platen, and means for bringing the platen and type together to produce an impression upon the paper; of means for absolutely preventing the advancement of said paper while the platen is within the entire range of printing effectiveness; and means for automatically feeding the paper when the platen is beyond the range of printing effectiveness.

3. In a printing attachment, the combination with type carriers, a paper support, a platen, and means for bringing the platen and type together to produce an impression upon the paper; of means automatically rendered operative at each operation of the machine for preventing the advancement of the paper after the printing impression has once been taken.

4. In a printing attachment, the combination with type carriers, a paper support, a platen, and means for bringing the platen and type together to produce an impression upon the paper; of means for automatically feeding the paper; and means for locking said feed from operation after the printing impression has once been taken and until the normal feed movement takes place.

5. In a printing attachment, the combination with type carriers, a paper support, a platen, and means for taking a plurality of successive impressions from said type carriers at each operation of the machine; of means for preventing the advancement of the paper between said successive impressions.

6. In a printing attachment, the combination with type carriers, a paper support, a platen, and means for taking a plurality of successive impressions from said type carriers at each operation of the machine; of means for feeding the paper at each operation of the machine; and means for locking the feed between said successive impressions.

7. In a printing attachment, the combination with type carriers, a paper support, a platen, and means for taking a plurality of successive impressions from said type carriers at each operation of the machine; of means for automatically feeding the paper at each operation of the machine with provisions connected therewith for permitting the printing movement independently of the feed between the said successive impressions; and means for locking the feed to prevent advancement of the paper by hand between said successive impressions.

8. In a printing attachment, the combination with type carriers, and a movable paper

supporting carriage carrying a platen roller and means for reciprocating said carriage a plurality of times at each operation of the machine to secure successive impressions upon the paper; of means for feeding the paper; and means for locking the feed between the successive impressions.

9. In a printing attachment, the combination with type carriers, and a movable paper supporting carriage carrying a platen roller and means for reciprocating said carriage a plurality of times at each operation of the machine to secure successive impressions upon the paper; of means for automatically feeding the paper by the movement of said carriage with provisions connected with said feeding means for permitting the movement of the carriage between said successive impressions without causing the actuation of the feed; and means for locking the feeding means to prevent advancement of the paper by hand between said successive impressions.

10. In a printing attachment, the combination with type carriers, a paper support, and a platen; of means for feeding the paper; and means controlled by the movement of said platen for locking the feed to prevent advancement of the paper.

11. In a printing attachment, the combination with type carriers, a movable carriage carrying a platen roller, detail strip rollers mounted upon said carriage, and means for reciprocating said carriage to carry the detail strip against the type twice upon each operation of the machine; of a locking device carried upon said carriage and actuated by the movement thereof to lock the detail strip from advancement by hand between the successive impressions.

12. In a printing attachment, the combination with type carriers, a movable carriage carrying a platen roller, detail strip rollers mounted upon said carriage, and means for reciprocating said carriage to carry the detail strip against the type twice upon each operation of the machine; of means for feeding said detail strip; and a locking device mounted upon said carriage and actuated by the movement thereof to engage said feeding device and lock the same to prevent the advancement of the strip by hand between said successive impressions.

13. In a printing attachment, the combination with type carriers, a movable carriage carrying a platen roller, detail strip rollers mounted upon said carriage, and means for reciprocating said carriage to carry the detail strip against the type twice upon each operation of the machine; of a ratchet wheel connected with one of said detail strip rollers; a feeding device for feeding the strip by the movement of said carriage; a locking pawl for engaging said ratchet wheel; and a relatively stationary projection engaged by said pawl upon the movement of the carriage to cause the pawl

to engage said ratchet wheel and thereby lock the strip from advancement.

14. In a printing attachment, the combination with type carriers, a movable carriage carrying a platen roller, detail strip rollers mounted upon said carriage, and means for reciprocating said carriage to carry the detail strip against the type twice upon each operation of the machine; of ratchet wheels connected with said detail strip rollers, and feeding devices engaging one of said ratchet wheels for feeding the strip by the movement of the carriage; locking pawls mounted on said carriage and situated in juxtaposition to said ratchet wheels; and a relatively stationary projection projecting between said pawls and coöoperating therewith for causing the pawls to be spread apart by the movement of said carriage in such manner as to engage said ratchet wheels and thereby lock the detail strip from advancement.

15. In a printing attachment, the combination with type carriers, a paper feeding means,

a platen, and means for bringing the platen and type together to produce an impression 25 on the paper; of means for preventing the operation of the feeding means while the platen is within the range of printing effectiveness.

16. In a printing attachment, the combination with type carriers, a paper feeding means, a platen and means for bringing the platen and type together to produce an impression on the paper, of means for preventing the operation of the paper feeding means 35 while the platen is within the range of printing effectiveness, and means for automatically feeding the paper when the platen is beyond the range of printing effectiveness.

In testimony whereof I affix my signature 40 in the presence of two witnesses.

WILLIAM MURPHY.
